Ab Richardson Atty:

UNITED STATES PATENT OFFICE

HENRY G. EISLER, OF WILMETTE, ILLINOIS

FLOOR CONSTRUCTION

Application filed January 19, 1929. Serial No. 333,724.

My invention relates in general to improvements in floor construction, and the object of the invention, generally stated, is to provide a sound-proof floor which is particularly desirable for apartment buildings and other places where rooms must be insulated against noises produced on the floor above.

A feature of the invention is a floor construction comprising the usual sub-floor and finished floor, together with means for preventing the transmission of sound vibrations from the finished floor to the sub-floor and thence to the ceiling of the room below. This is accomplished in a practical and efficient manner and without resorting to radical changes in general design which might be objectionable to architects and contractors.

An ancillary feature is a new and improved nailing strip or sleeper intended to be manufactured and sold for use in building sound-proof floors.

The foregoing and other features of the invention will be fully described hereinafter, reference being had to the accompanying drawing, in which:

Fig. 1 shows a section of a floor embodying the invention;

Fig. 2 is an enlarged section taken on the line 2—2, Fig. 1;

Figs. 3 and 4 are top and bottom views, respectively, of my improved nailing strip or sleeper; while

Fig. 5 is a sectional view similar to Fig. 2 except that it shows a modification of the invention.

Referring to Fig. 1, the reference numeral 3 indicates a portion of a floor joist. The floor joists, as is well understood, extend transversely across the building, spaced perhaps 16 inches apart. The drawing, Fig. 1, is fragmentary, and shows only a small portion of one joist. The reference character 4 indicates the sub-floor, generally made of rough lumber laid directly on the joists and nailed thereto.

In order to support the finished floor, so-called nailing strips or sleepers are provided. These are laid on the sub-floor, preferably directly over the joists. The drawing shows a portion of one nailing strip 5, and a section

of finished flooring 6. The nailing strips may be about 2 x 2 inches in cross section, or somewhat smaller, depending on how much space is required for the laying of conduit. As will shortly appear, the nailing strips are of an improved construction and form a principal part of my invention.

One nailing strip is shown in Figs. 3 and 4. Fig. 3 is a top view, while Fig. 4 shows the lower side with sound insulators in place. As stated before 2 x 2 inch material may be used, cut to standard lengths, 10 or 12 feet, or longer. Each strip is bored and counter-bored as shown in Figs. 3 and 2, the holes being spaced on 16-inch centers. The spacing may, of course, be varied and a closer spacing should be used in the case of nailing strips which are to form part of a floor subject to heavy strains.

The holes in the nailing strips are provided to accommodate my improved sound-proofing means, which will now be explained, reference being had especially to Figs. 4 and 2. As shown in Fig. 4, each hole in a nailing strip has inserted therein a cushioning member 7, of sound-proof material. The members constitute sound or vibration insulators. One of the insulators 7 is shown quite clearly in the sectional view, Fig. 2. It comprises a round base portion having its diameter approximately equal to the width of the nailing strip, and a perforated shank of the proper size to fit the hole in the nailing strip. This shank may be long enough to extend perhaps half way through the nailing strip. Accompanying each insulator 7 is a washer 8, also composed of vibration insulating material. The washers 8 are of the proper size to fit snugly in the recesses which have been formed in the upper surface of the nailing strip by the counter-boring operation.

The cushioning members or insulators 7 and the washers 8 may be made of various sound-proof materials. I prefer, however, to use a good grade of rubber, what is known as tire tread stock, and form the parts by vulcanizing in molds. The parts thus formed are inexpensive, are convenient to handle, and at the same time they form an ideal cushion-

ing means for preventing the transmission of sound vibrations.

In building a floor embodying my improved sound-proofing means, the sub-floor is laid in the usual manner, when the carpenter will be ready to proceed with the nailing strips. These may be nailed down to the sub-floor, one over each joist. The process of laying my improved nailing strip is not especially complicated, but it may, nevertheless, be briefly explained. After making certain that an insulator 7 is inserted in each of the holes, the strip is placed in the proper position on the sub-floor, as indicated in Fig. 1. The washers 8 may now be placed in the recesses on top of the strip, if they have not previously been inserted. The strip may now be nailed down, one nail being used at each point where an insulator is located. Before driving a nail, care should be taken to thread on an iron washer such as 9. The nail may then be passed through the central openings in the washer and insulator and driven home into the sub-floor, as indicated in Fig. 2. Each nail should be driven in tight enough to slightly compress the associated washer 8. The nailing strips having all been placed as described in the foregoing, the job is ready for the finished flooring, which is laid on the nailing strips and nailed down piece by piece in the usual manner.

The completed floor is proof against the transmission of sound vibrations because the finished floor and the nailing strips to which it is attached are fully insulated from the sub-floor. The entire weight of the upper floor and objects supported on it is carried by the insulators 7, which form the principal insulating means. The nails such as 10, which secure the nailing strips to the sub-floor and which would have a tendency to conduct vibrations through to the sub-floor, are prevented from having this undesirable effect by the washers 8. Thus, as stated, the finished floor and nailing strips are entirely insulated, even though the latter are securely nailed to the sub-floor.

In carrying out my invention, I contemplate fabricating the nailing strips at a wood working mill, where they can be conveniently bored and counter-bored by machinery, and put up in bundles for sale to the trade. The nailing strips may be put out fully equipped with insulators 7 and washers 8 all assembled in place if desired. This enables the nailing strips to be placed with a minimum of extra labor; in fact, if furnished complete the nailing strips can be laid practically as fast as plain uninsulated strips.

Fig. 5 shows a modification of the invention which is desirable under certain conditions. The parts shown in Fig. 5 correspond generally to those shown in Fig. 2 and hence an extended description will not be necessary. It may be pointed out, however, that

the insulator 7 of Fig. 2 is replaced by an insulating member 17 in which the shank portion is omitted, while the insulating washer 8 is replaced by an insulator 18 which is provided with a shank. In other words, the shank portion, which positively separates the nail from the sides of the opening, is moved from the lower to the upper insulator. Insulators such as 8 can be used along with the insulators 17, but more care has to be exercised in driving the nails accurately. 75 75

It will be seen from the foregoing that I have devised a very efficient sound-proof floor, and provide inexpensive and very convenient means for constructing it. While I have described with particularity a certain specific form of my invention, so that the same can readily be practiced, it will be understood that the parts are capable of modification and need not be precisely as illustrated in the drawing, which is intended only as an example. I do not, therefore, wish to limit myself to the exact embodiment of the invention which is shown and described, but desire to include and have protected by Letters Patent all forms of my invention which come within the scope of the appended claims. 80 90 95

What is claimed is:

1. The combination, with a nailing strip, of means for insulating said strip from the sub-floor and for attaching said strip to the sub-floor, said means comprising a perforated insulator lying between the strip and the sub-floor and having a portion embedded in the strip, a perforated insulating washer embedded in the said strip near the upper surface thereof, and a nail passing through the perforations in said washer and said insulator and driven into the sub-floor. 100 105

2. A floor construction comprising a sub-floor, nailing strips laid on said sub-floor, a series of spaced vibration insulators inserted between each nailing strip and the sub-floor, securing devices extending through each nailing strip to the sub-floor at the points where said insulators are located, means for insulating said devices from the nailing strips, and a top floor laid on said nailing strips. 110 115

3. A floor construction comprising a sub-floor, nailing strips having openings therein, nails having insulated heads passing through said openings and driven into the sub-floor, an insulator concentric with each nail and positioned between the associated nailing strip and the sub-floor, and a top floor laid on said nailing strips. 120 125

4. As an article of manufacture, a nailing strip having a series of holes extending through it from top to bottom, said holes being counter-bored to form recesses on the top side of said strip, insulating washers inserted in said recesses, and supporting insulators having cylindrical shanks inserted in said holes on the bottom of said strip. 125

5. The combination, with a nailing strip 120

adapted to be nailed to a support, of an insulator, said insulator comprising a base portion for supporting the nailing strip and a shank portion adapted to encircle a nail and insulate it from the strip.

5 6. The combination, with a nailing strip having holes therein through which nails may be driven to attach the strip to a support, of a pair of bushings for each hole to insulate the strip from the nails, one bushing of each pair serving also as a support for the strip.

10 7. The combination, with a nailing strip having holes therein through which nails may be driven to attach the strip to a support, of means for insulating the head of each nail from the strip, each said means comprising a metal washer and an insulating washer threaded on the associated nail, and recesses in said strip concentric with the holes 15 for receiving said washers.

20 In witness whereof, I hereunto subscribe my name this 16th day of January, A. D. 1929.

HENRY G. EISLER.
